UNITED STATES PATENT OFFICE.

FRANCES MACKAY, OF NORWALK, CONNECTICUT.

DESIGN FOR A BOY'S SUIT.

60,942.

Specification for Design.

Patented May 9, 1922.

Application filed October 20, 1921. Serial No. 509,181. Term of patent 14 years.

To all whom it may concern:

Be it known that I, FRANCES MACKAY, a citizen of the United States, and a resident of Norwalk, in the county of Fairfield and State of Connecticut, United States of America, have invented a new, original, and ornamental Design for a Boy's Suit, of which the following is a specification, reference being had to the accompanying drawing, in which—embodying my new design, the coat and hood part being shown closed;

Figure 2 is a similar view on a reduced scale with the coat and hood shown open.

The new design resides in the coat front and in the hood, as shown.

I claim:

The ornamental design for a boy's suit, as shown.

FRANCES MACKAY.
